UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

DEVICE FOR EQUALIZING PRINTING IMPRESSIONS.

Application filed April 27, 1925. Serial No. 25,976.

My prior Patent No. 1,451,204 issued April 10, 1923, to the American Multigraph Company shows a printing form adapted for mounting on a rotary drum and comprising a sheet metal plate having upstanding overhanging rows of projections which are surmounted by embossed printing strips having inwardly flanged edges adapted to overhang the projections. Such a flexible form may be readily mounted, for example, on a multigraph drum and print through an inking ribbon extending over the form. In such operation, the printing lines lie parallel with the printing axis and coat one at a time with a roller platen to impress paper between them. It results from this that very short lines, such as sometimes come at the end of a paragraph or in the salutation, make a heavier impression than the body of the form where the lines are of approximately the same length.

The object of this invention is to provide a simple attachment adapted for mounting on this flexible blanket and serving to relieve the pressure on the short lines. To this end, I have provided a device having two parallel strips connected at one end, and separated a short distance, the understrip being adapted to rest on top of a row of projections, and having means to hold it on the blanket and the upper strip adapted to overlie the ribbon. When the upper strip is pressed against the ribbon, during the printing impression, its outer surface stands the same height-to-the-paper as the ribbon normally stands when it engages the form.

When my pressure equalizer is inserted in alignment with a short line, the printing pressure at such time is taken partly at the short line and partly by the equalizer, with the result that practically the same support for the pressure is provided as in a line of normal length, and accordingly the short lines print with the same depth of impression as the other lines.

The base member of my equalizing device may be provided with inward flanges to underhang the projections on which the strip rests or with outward flanges to underhang the projections of adjacent rows. In either case, however, the base member rests on top of the row of projections which carries the short embossing printing strip. Each form is illustrated herein and is covered by the claims hereof.

In the drawings Fig. 1 is a vertical section through a multigraph machine equipped with my flexible blanket and one of my equalizers; Fig. 2 is a plan of a portion of such drum showing one of the equalizers in place; Fig. 3 is a cross-section on the line 3—3 of Fig. 2; Fig. 4 is a perspective of the equalizer having the inward edge flanges as shown in Fig. 2; Fig. 5 is an enlarged end view of the equalizer shown in Fig. 4; Fig. 6 is an enlarged cross-section of the blanket, embossed strips and one of my inwardly flanged equalizers on a flat form; Fig. 7 is a similar cross-section showing the equalizer with the outward flanges; Fig. 8 is a perspective of the equalizer with outward flanges; Fig. 9 is a cross-section through a portion of a railed segment usual in the multigraph, equipped with my blanket and each form of equalizer.

In Figs. 2, 3, 6, 7 and 9, the numeral 10 indicates the flexible blanket, which may well be of the form substantially shown in my patent referred to, and comprises a sheet of metal having rows of upstanding buttons 11, which are connected at opposite edges in the line of the row with upstanding corrugations 12, the edges of the buttons at the sides of the corrugation 13 being disconnected from the body of the plate and standing some distance above it. Such form of type holder is more fully described in Patents No. 1,438,584 and No. 1,438,582, issued December 12, 1922, on applications of William J. Demming and Burnie J. Craig respectively.

Mounted on the rows of buttons are embossed printing strips 20, each made of sheet metal and having upstanding projecting printing characters, and having inwardly extending edge flanges which extend beneath the overhanging buttons, and thereby hold the strip in place. A holder having projections with such strips mounted thereon is covered in my Patent No. 1,438,580 issued December 12, 1922. Such strip may be produced in any suitable machine, as for example that illustrated in my application No. 535,311, filed February 9, 1922, which also claims the strip per se.

Referring now to Figs. 1 to 6 inclusive, my equalizer is shown as comprising a lower or base strip 30 having inwardly flanged edges 31, and an upper or pressure strip 32 lying a short distance above the strip 30,

and connected with it at one end. To effect the connection, I prefer to mount a filler block 33 beneath the body of the base strip 30 adjacent one end; to offset downwardly the end portion of the pressure strip 32 as at 34, and to extend two rivets 35 through the top strip, the bottom strip and the filler block. These rivets may be counter sunk in the filler block and the top strip.

10 The base strip is made of any suitable metal of sufficient stiffness to hold its shape, while the top strip is of a spring steel and has a tendency to spring slightly away from the bottom strip.

15 In use, the equalizer is slipped endwise over the row of buttons which carry the short lines desired to be equalized, the joined end of the equalizer being beyond the blanket. The ribbon, designated A, is then passed over the body of the form but beneath the top strip of the equalizer. In this position the top surface of the equalizer is in the same plane with the top of the ribbon where it overlies the short line, as

20 clearly illustrated in Fig. 3. Accordingly, whenever the printing pressure comes on this line, the pressure is substantially the same as if it were of full length.

25 By making the top strip of steel, it does not bind the ribbon, except at the instant of impression, and accordingly the ribbon is free to be periodically fed during the rotating of the machine. As is usual in the multigraph, such feed taking place at a time when the form is out of coaction with the platen.

30 In the form of equalizers shown in Figs. 7 and 8, the top strip 32 is identical with that just described, but the base strip 36 instead of having its flanges extending diagonally inward, has downward, slightly flaring portions 37 at the bottoms of which are outward flanges 38. The two flanges 38 are adapted to underlie the projections of adjacent rows of buttons instead of the projections on which the body of strip rests. The top strip is riveted to the body of the bottom strip as at 35 by rivets which pass through these two strips and through a reinforcing block. This reinforcing block is shown at 39 in Fig. 8 when the sides 37 and the flanges 38 are shown as cut away at this end to allow a wider filler block.

35 In the form of equalizer just described, the base strip may be readily manufactured by a single operation of stamping, but it has a disadvantage that it is not applicable to single space work on the blanket, but requires vacant rows of buttons on opposite sides of the row carrying the short line.

40 It will be seen that my equalizing device, made in either form shown, is adapted for 65 ready use with the flexible blanket mounted

on its support without any change whatever in either the support, the blanket or the embossed strips. Such equipped blanket may be mounted on a smooth drum as shown at 40 in Fig. 1; on a plate as shown at 41 in Figs. 6 and 7, or on rails 42 of a multigraph drum as shown in Fig. 9.

45 Fig. 1 illustrates a machine similar to a multigraph having a segment 40 clamped on a skeleton drum 44 mounted on a rotary driving shaft 45, and a pair of ribbon spools 46 mounted within the drum to carry the ends of the ribbon. The form covered by the ribbon coacts with the rubber faced roller platen 47. A suitable mechanism not shown may feed this ribbon periodically by rotating one spool or the other. For a further description of such a machine, and particularly of means for feeding the ribbon, reference may be made to Patent No. 997,287, issued July 10, 1911, to the American Multigraph Company.

50 Having thus described my invention, I claim:

1. The combination of a type holder having rows of overhanging projections, embossed printing strips mounted on the projections of the different rows and having inwardly projecting edge flanges to extend beneath said projections, and an equalizing device for short lines comprising a body adapted to rest on top of a row of projections and provided with means for holding it in place thereon, and a strip parallel with the body and a short distance above it, connected with it beyond the edge of the type form, said upper member adapted to overlie a ribbon which passes over the type form and over the body of said device.

2. The combination of a holder having projections, embossed printing strips resting on such projections and having inward edge flanges extending beneath them, an equalizing device comprising a base member adapted to rest on top of a projection and having edge flanges for holding it in place, and a top member secured at one end to the base member and adapted to overlie a ribbon.

3. The combination of a type holder having raised portions, embossed printing strips mounted on the raised portions, and an equalizing device for short lines comprising a body adapted to rest on a raised portion and provided with means for holding it in place thereon, and a strip parallel with the body a short distance above it and connected with it beyond the edge form, the combined thickness of the body and top strip being equal to the thickness of an embossed strip plus the height of the printing characters above the body of such embossed strip.

4. The combination of a type holder having overhanging projections, embossed

printing strips mounted on the projections and having inwardly projecting edge flanges to extend beneath said projections, and an equalizing device for short lines comprising
5 a body adapted to rest on a projection and provided with edge flanges for holding it in place thereon, and a strip parallel with the body a short distance above it and connected with it beyond the edge of the type
10 form, said top strip being of spring material to enable it to automatically relieve pressure on the ribbon when it is out of printing coaction.

5. The combination of a printing couple
15 adapted to have rolling coaction, a removable type holder mounted on one member of the type couple and having upstanding projections arranged in rows, embossed printing strips mounted on said projections,
20 an inking ribbon adapted to be extended across such strips, and a pressure equalizer mounted on a row of projections in alignment with a short strip and having a top strip adapted to overlie the ribbon, said
25 top strip standing at the same height-to-paper as the ribbon over the short strip.

6. An equalizing device of the character described comprising a body strip having flanged edges, and a top strip some distance
30 above the body strip and connected to it at one end.

7. An equalizing device of the character described combining a body strip equipped with means for holding it in place and the

top strip some distance above the body strip 35 and made of spring material and connected at one end to the body strip.

8. In a device of the character described, comprising a base strip having flanged edges, a spring metal top strip having a 40 downwardly offset portion at one end, and means for connecting said offset portion with the end portion of the base strip.

9. In a device of the character described, the combination of a base strip having 45 flanged edges, a top strip some distance above the base strip for the greater portion of its length, the top strip and base strip being in engagement adjacent the end, and rivets passing through such engaging portions.

10. An equalizing device of the character described comprising a base strip having inwardly flanged edges, and a top strip some 50 distance above the base strip and connected to it at one end.

11. In a device of the character described, the combination of a base strip having inwardly flanged edges, a top strip of spring 60 steel some distance above the base strip for the greater portion of its length, the top strip being downwardly offset adjacent the end, and rivets passing through such end portion to connect the two strips together.

In testimony whereof, I hereunto affix my 65 signature.

CLIFTON CHISHOLM.
